UNITED STATES PATENT OFFICE.

GEORGE H. WHEARY, OF RACINE, WISCONSIN, ASSIGNOR TO THE HARTMANN TRUNK COMPANY, OF RACINE, WISCONSIN, A CORPORATION OF WISCONSIN.

TRUNK.

1,119,133.

Specification of Letters Patent.

Patented Dec. 1, 1914.

Application filed April 12, 1912. Serial No. 690,327.

To all whom it may concern:

Be it known that I, GEORGE H. WHEARY, a citizen of the United States, and resident of Racine, in the county of Racine and State 5 of Wisconsin, have invented new and useful Improvements in Trunks, of which the following is a description, reference being had to the accompanying drawings, which are a part of this specification.

10 This invention relates to improvements in trunks and more particularly to the manner of forming the frame and corners of trunks.

It is one of the objects of the invention to 15 provide a trunk in which the frame and corner portions thereof are of greater rigidity and strength than trunks of ordinary construction and will resist greater strains.

A further object of the invention is to 20 construct a trunk in which the corner post connections thereof are so formed as to reinforce the whole trunk and provide the maximum strength with the minimum amount of material and labor.

25 A further object of the invention is to provide a trunk in which the ends of the panels or boards forming the trunk are covered by the peculiar formation of the corner posts to which they are fastened.

30 With the above and other objects in view, the invention consists of the improved trunk and its parts and combinations, as set forth in the claims, and all equivalents thereof.

In the accompanying drawing in which 35 the same reference characters indicate the same parts in all of the views: Figure 1 is a perspective view of the improved trunk, some of the panels being removed to show interior construction; Fig. 2 is a vertical 40 sectional view of one end of the trunk, portions of the trunk being separated to more clearly illustrate the formation of the posts; Fig. 3 is a horizontal sectional view of one end of the trunk, taken on line 3--3 of Fig. 4, with portions also separated to illustrate 45 details of construction; Fig. 4 is a side detail view, on a larger scale, of one of the upper side corners of the trunk; and Fig. 5 is a similar view of the top of an upper corner.

50 Referring to the drawing the numeral 8 indicates the vertical corner posts, 9 the upper and lower side rails, and 10 the upper and lower end rails of the reinforcing frame

of the improved trunk. The posts are divided horizontally, to provide for the body and lid portions of the trunk, and are joined together by ordinary hinges 11 and the usual furnishings when completed as a trunk. The molding from which the posts 60 and rails are made has a cross section of the form of a right-angled triangle with the right angle rounded off. The rabbets are then formed in the sides adjacent the rounded portion to a depth corresponding to 65 the thickness of panels extending into the rabbeted portions to form a flush outer surface with the rounded corner portion. The rabbeted portions of the posts and rails are indicated by the numerals 12 and 13 respectively, and the panels by the numeral 14. The ends 15 of the upper and lower rails are mitered to form upper and lower rectangular frames 16, and the mitered ends 17 of the rabbeted portions of the rails are cut 70 horizontally at right angles with respect to the line of the miter joints to accommodate the end portions 18 of the corner posts 8 which are overlapped on the ends by the mitered end portions of the unrabbeted ends 80 of the rails, and on their inner faces by the ends of the rabbeted portions of the rails. The rectangular frames are fastened to the posts by nails 19 which are driven through the corners of the rails and into the ends 85 of the posts. The panels 14 are set into the seats or recesses 19', formed by the rabbeted portions of the posts and rails, and are nailed thereto by nails 20 which are driven obliquely through the end portions of the 90 panels and into the posts and rails. As the end portions of the panels abut against the shoulders 21 of the rabbeted portions of the posts and rails, torsional or twisting strains are resisted to a considerable extent and 95 the obliquely driven nails also serve to bind the parts together more intimately and are less liable to work out.

The outer corners of the posts and rails are rounded to form larger and stronger 100 contacting edges and to give the trunk a more ornate appearance than with the ordinary square cornered construction.

From the foregoing description it will be seen that the panels are wholly within the 105 reinforcing frame and do not engage each other as in ordinary construction, and as the panels are each fastened to the compara-

tively strong and heavy frame the resultant structure is stronger and possesses strain resisting qualities over the ordinary trunks.

What I claim as my invention is:

- 5 1. A trunk, comprising an upper and a lower rectangular reinforcing frame formed of lengths of rabbeted material approximately triangular in cross section and having mitered corners, the rabbets being
10 formed in the right angled portions and the corner edges and forming panel recesses, the outer mitered corner portions of the rabbeted portions forming post recesses, corner posts spacing the frames apart and having
15 their end portions extending into the post recesses and overlapping the mitered corners, said posts also being formed of lengths of rabbeted material approximately triangular in cross section, the rabbeted portions
20 being formed in the right angled portions and the corner edges, the rabbeted portions of the posts and the rectangular frames forming outer side and end panel recesses, and panels inserted in all of said recesses,
25 and fastened to the frames and to the corner posts.

2. A trunk, comprising an upper and a lower rectangular reinforcing frame formed of lengths of rabbeted material approximately triangular in cross section and having mitered corners, the rabbets being
30 formed in the right angled portions and the corner edges, parts of the outer mitered corner portions of the rabbeted portions of each
35 corner being cut away in a line extending at right angles to the line of the miter joint to form post recesses, corner posts spacing the frames apart and having their end portions extending into the post recesses and over-
40 lapping the mitered corners, said posts also being formed of lengths of rabbeted material approximately triangular in cross section, the rabbeted portions being formed in the right angled portions and the corner
45 edges, the rabbeted portions of the posts and the rectangular frames forming outer panel recesses, and panels inserted in all of said recesses and fastened to the frames and to the corner posts.

50 3. A trunk, comprising an upper and a lower rectangular reinforcing frame formed of lengths of rabbeted material approximately triangular in cross section and hav-

ing mitered corners, the rabbets being formed in the right angled portions and the corner edges, parts of the outer mitered corner portions of the rabbeted portions of each corner being cut away in a line extending at right angles to the line of the miter joint to form post recesses, corner posts spacing the frames apart and having their end portions extending into the post recesses and over the mitered unrabbeted portions of the joints and having their inner faces bearing against the angularly cut rabbeted ends of the corner portions of the frames, means for securing the rectangular frames to the posts, said posts also being formed of lengths of rabbeted material approximately triangular in cross section, the rabbeted portions being formed in the right angled portions and the corner edges and said rabbeted portions registering with and being flush with the rabbeted portions of the rectangular frames to form outer panel recesses, and panels inserted in all of said panel recesses and fastened to the frames and to the corner posts.

4. A reinforcing frame corner construction for a trunk, comprising a pair of rabbed frame members approximately triangular in cross section, the rabbets being formed on two faces of the member in the right angled portions and the corner edges, said members being mitered and joined together to form a right angled corner, parts of the outer rabbed mitered corner portions of the members on one face being cut away in a line extending at right angles to the line of the joint to form a post space, and a square ended rabbed post extending into said space and abutting against both members and having a portion of its un-rabbed face bearing against the angularly cut rabbed portions of the members, said post being approximately triangular in cross section with the rabbed portions formed in the angled portions and the corner edges, the rabbed portions forming outer panel recesses.

In testimony whereof, I affix my signature, in presence of two witnesses,

GEORGE H. WHEARY
